CLAIM

The ornamental design for a wearable microcurrent device, as shown and described.

DESCRIPTION

FIG. 1 is a front isometric view of a wearable microcurrent device.

FIG. 2 is a rear isometric view of the wearable microcurrent device of FIG. 1.

FIG. 3 is a front elevation view of the wearable microcurrent device of FIG. 1.

FIG. 4 is a rear elevation view of the wearable microcurrent device of FIG. 1.

FIG. 5 is a left side elevation view of the wearable microcurrent device of FIG. 1.

FIG. 6 is a right side elevation view of the wearable microcurrent device of FIG. 1.

FIG. 7 is a top plan view of the wearable microcurrent device of FIG. 1; and,

FIG. 8 is a bottom plan view of the wearable microcurrent device of FIG. 1.

The parallel lines at the transitions between surfaces are intended to illustrate a transition that can include smooth rounding or bevel facets in the transition. The closely spaced, parallel, curved lines visible at the two surfaces in the top portion of FIG. 4 indicate a shallow surface pattern, also visible from the side in FIGS. 5–8.
